UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

APPARATUS FOR APPLYING A COVER TO A CASING.

1,417,155.

Specification of Letters Patent. Patented May 23, 1922.

Application filed May 5, 1921. Serial No. 467,080.

To all whom it may concern:

Be it known that I, CHARLES FISHER, a citizen of the United States, residing at Chicago, in the county of Cook and State of Illinois, have invented a new and useful Improvement in Apparatus for Applying a Cover to a Casing, of which the following is a specification.

The present invention relates particularly to apparatus for use in binding or covering a metal casing of a book-form safe.

My primary object is to provide improved and simple apparatus adapted for the purpose indicated.

15 The invention is adapted to the purpose of applying a cover to a casing of U-form cross-section, such a casing being indicated in Fig. 4 of the accompanying drawings. The invention is illustrated in its preferred embodiment in the drawings, in which—

Fig. 1 represents a plan view of a device embodying the invention; Fig. 2, a front elevational view of the same; Fig. 3, a vertical longitudinal sectional view taken as indicated at line 3 of Fig. 1; Fig. 4, a broken perspective view showing the bed of the machine with a cover for the casing spread thereon, and showing also the casing of the safe and one of the side pads which is applied inside the cover; Fig. 5, a broken perspective view showing the upper ironing and pressing member in the lowered position and partially hiding the casing which is being covered; Fig. 6 a broken perspective view of the bed, showing also the folding of the cover over the casing as the latter rests in position in the form in the bed; Fig. 7, a broken perspective view illustrating the means for forcing the flaps of the cover inwardly at the edges of the casing, in which operation the flaps or margins of the cover are ironed over the inner margins of the metal, the inner margins of the metal being coated with a suitable glue or cement to cause the margins of the cover to adhere thereto; Fig. 8, a perspective view of the casing after the operation of applying the cover has been completed; Fig. 9, a perspective view of a closure for the casing; and 50 Fig. 10, a perspective view of the safe after the closure has been applied.

The casing which is to be covered is shown in Fig. 4, and is designated A. It comprises a sheet metal member bent into U-form to

simulate the sides and back of a book. Thus, 55 the casing comprises side plates 1 and a back 1^a. The sides 1 are connected together near the edges of the metal by posts 1^b. The cover which is to be applied to the casing is designated 2, and one of the cotton batting 60 or felt pads which are to be interposed between the cover and the sides of the casing is illustrated in Fig. 4, being designated 3. The corners of the cover are cut away on oblique lines, but there are left projecting 65 corner tabs 2^a which furnish the material which is to be folded over the corners of the metal. After the cover has been folded over the back and both sides of the casing and over the edges of the metal, it furnishes end 70 edge flaps, or margins, 2^b, longitudinal edge flaps 2^c and tucks or folds 2^d.

In the embodiment of the apparatus shown for applying the cover, B represents a bed which is secured to a bench 4, said bed having applied thereto a plate B' provided with a form-depression B² which conforms to the outline of the safe-casing; C, clamping devices pivotally mounted on the bed B and adapted to clamp the lower wall of the casing and the infolded lower flaps 2^b to the bed; and D an upper ironing and pressing member which is carried by a plate D' which has its lower or rear end equipped with a transverse pivot rod D² which is capable of 80 sliding in suitable guides D⁴ with which the bed is equipped on its upper side near its lateral edges.

The form-depression B² is of sufficient depth to accommodate the thickness of the 90 cover, the pad, and the metal plate constituting one side of the casing. At the rear end of the bed plate B' is secured a transverse strip 5 which projects above the bed plate and constitutes a rear stop or gage for 95 positioning the cover. The guides D⁴ are in the form of strips secured to the bed B and extending from the rear end of the bed to a point near the rear edge of the depression B². Thus, the front end portions of the 100 strips D⁴ are adapted to afford stops or gages for the edges of the cover 2. The front ends of the strips D⁴ are provided with slight recesses 6 adapted to serve as bearings for an implement of the character shown 105 in the left hand portion of Fig. 7, in the operation of folding the tucks 2^d inwardly. The pivot rod D² is adapted to slide in slots

7 with which the strips D⁴ are provided, and a transverse stop 8 is provided for limiting the forward movement of the ironing device D when this device comes into position to enable it to be pressed downwardly over the edges of the safe-casing.

The rear end of the bed B is equipped with a standard or post 9 which is adapted to support the device D in the standing position shown in Fig. 3. The bed is further equipped with a spring 10 over which the pivot rod D² rides when the device D is shifted rearwardly, the spring having a slight elevation near its rear extremity serving as a shoulder against which the pivot may rest when the device D is in standing position, but inclined rearwardly slightly.

The device D comprises a suitable block 11 equipped on its upper or back side with a knob or handle 11^a, by which the ironing and pressing device may be operated. The block 11 has secured to its edges a strip or band which affords a shallow flange 11^b at the lower side of the block when the device D is in its lowered position. Thus, the ironing member is provided with a form-depression 12 which is adapted to accommodate the upper side of the safe-casing, the upper pad, and the cover. The lateral edges of the block 11 are further equipped with strips 13 which afford guides or positioning members for centering the safe-casing initially over the form-depression B². To enable this to be done, the member D is lowered onto the bed while the pivot rod D² is at the rear end of its traverse; and the device D then presents a forwardly open socket or recess between the members 13 in which the rear edge of the lower pad and the back wall of the safe-casing may be positioned, thus bringing the pad and casing into position to be depressed into the form-depression B². When the casing is thus forced into the depression B², the lateral edge portions of the cover are bent up over the edges of the lower wall of the casing, and are then ironed inwardly over the inner margins of the metal by the members C, which members also operate to clamp the lower wall of the casing and the interposed cover to the bed plate. After this, the device D is returned to the standing position to enable the cover to be folded by the operator over the back wall and top wall of the casing. In this operation, the operator stretches the fabric tightly over the back wall of the casing, and then lowers the device D and pulls it, while exerting suitable pressure, forwardly over the upper covering, thus ironing the covering over the upper wall of the casing. When the member D reaches the forward end of its traverse, the operator depresses said member over the edges of the upper wall of the casing, the casing being received by the form-depression 12. This operation bends

the upper end flaps 2^b and the upper longitudinal flap 2^c downwardly over the edges of the upper wall of the casing.

The operator then uses the edge ironing device E shown in Fig. 7 to force the longitudinal flaps 2^c inwardly; then uses the implement F shown in Fig. 7 to fold the tucks 2^d inwardly against the back wall of the casing, first pressing the end flaps 2^b inwardly as much as may be necessary to enable the tucks 2^d to be properly inserted; then swings the arms of the device E inwardly to iron in the end flaps 2^b and the tucks 2^d; and finally employs the U-shape corner-ironing devices G (one shown in Fig. 7) to iron the corner tabs 2^a inwardly over the corners of the metal.

The device E comprises a front member 14 which is adapted to fold the longitudinal flaps 2^c inwardly and iron them over the inner margins of the metal; and pivoted side arms 15 adapted to iron the end flaps 2^b inwardly and at the same time iron the previously infolded tucks 2^d against the inner surface of the back wall of the casing. The arms 15 are provided at their free ends with inward projections 15^a which accomplish the ironing of the tucks 2^d. The extremities of the arms are also provided with finger pieces 15^b. The member 14 is provided at its inner edge with slotted lugs 14^a which are adapted to engage the posts 1^b of the casing, thus properly centering the member 14 when it is inserted; and the member 14 is further provided with a handle 14^b by means of which the device may be withdrawn after the cement is dry.

In using the tuck-inserting implement F, the operative end portion may be caused to bear against the surfaces afforded by the concave recesses 6 at the ends of the members D⁴ thus giving the necessary leverage.

The clips G (one shown) are of U-shape and composed of thin sheet metal. These clips are adapted to be inserted between the side walls of the casing at the corner portions and thus iron the tabs 2^a inwardly. The clips may be inserted while the device E is in position, it being understood that the arms of the clips embrace the corner portions (which are suitably recessed) of the device E when the device E is in the fully inserted position. To facilitate the insertion of the clips G, the bed plate B' is provided near its corners with oblique slots or recesses 16, which enable the operator to guide the clips at the proper angle.

It will be understood that the cover may be preliminarily blanked and impressed with any desired design. Fig. 8 shows the condition after the cover has been applied. In Fig. 9, H represents a closure which is adapted to be inserted and locked to the posts 1^b. This closure is of U-form and commonly made of brass, which is given a silken

finish to simulate the gilt edges of the leaves of a book. Fig. 10 shows the safe with the closure locked in place.

By means of the improved apparatus, a safe-casing of the character referred to may be expeditiously and neatly covered; and when the closure shown in Fig. 9 is inserted, the whole device closely simulates the appearance of a book.

10 Each of the clamping devices C comprises an arm 17 which is connected, by a pivot 18, to the upper surface of the lateral margin of the bed plate, and a furcated finger or projection 19 mounted on the free extremity 15 of the member 17 and extending at right angles thereto. The furcated finger 19 is adapted to work over the bed plate B' and slip over the lower wall of the safe casing and the infolded end flap 2^b, as shown in 20 Fig. 5. The member 19 is equipped with a finger piece 19^a for convenience in swinging the clamping member inwardly and outwardly. The lateral edges of the bed B are equipped with segmental supports 20 which 25 serve as rests for the clamping devices C when they are swung on their pivots. The finger 19 has a lower fork 19^b which is adapted to enter a slot 19^c in the lower side of the plate B'.

30 It will be understood that after the ironing and pressing device D has been used to iron the cover over the upper wall of the casing and fold the marginal portions of the cover downwardly, the clamping devices C 35 are swung outwardly from the bed plate, after which the operations indicated in Fig. 7 may be performed. The device D will serve to hold the casing in proper position, and after it is no longer needed for such 40 purpose, the device D may be moved to the position shown in Fig. 3.

The improved device may be used for various purposes, as for binding cover-sections of memorandum books, etc. Here the cover-sections of the book correspond with the sides of the safe, and any suitable means may be employed for spacing the cover-sections during the binding operation.

The foregoing detailed description has 50 been given for clearness of understanding only, and no unnecessary limitations should be understood therefrom, but the appended claims should be construed as broadly as permissible in view of the prior art.

55 What I regard as new, and desire to secure by Letters Patent, is:

1. In means of the character set forth, the combination of a bed provided with means for positioning a cover and with a form-depression, means for clamping one wall of a casing and the folded margins of one portion of a cover to said bed, and an upper ironer provided with means for folding the margins of the other portion of the cover

over the edges of the upper wall of said 65 casing.

2. In means of the character set forth, the combination of a bed provided with means for positioning a cover and with a form-depression, means for clamping one wall of a casing and the folded margins of one portion of a cover to said bed, an upper ironer provided with means for folding the margins of the other portions of the cover over the edges of the upper wall of said casing, 70 and means for tucking the folded margins of the cover inwardly against the inner margins of the walls of the casing.

3. In means of the character set forth, the combination of a bed provided with a form-depression and with means for positioning a cover, and a pivotally and slidably mounted pressing and ironing device adapted to iron the cover over the upper side of a casing and depress the margins of the cover over 80 the edges of said upper wall.

4. In means of the character set forth, the combination of a bed provided with a form-depression and with means for positioning a cover, and a movably mounted upper pressing and ironing device adapted to iron the cover over the upper wall of a casing and depress the margins of the cover over the edges of said upper wall, said device being equipped with means for positioning the 95 casing over said form-depression and upon the cover held by said bed.

5. In means of the character set forth, the combination of a bed provided with a form-depression and with means for positioning a 100 cover, a pair of clamping members pivotally connected with and flanking said bed and adapted to fold the margins of one portion of the cover over the end edges of the lower wall of a casing and clamp said casing to 105 said bed, and a pivotally and slidably mounted ironing and pressing device coacting with said bed and provided with a form-depression adapted to accommodate the upper wall of the casing.

6. In means of the character set forth, the combination of a bed provided with a form-depression and with means for positioning a cover, means for clamping the lower wall of a casing in said form-depression, and an 115 upper ironing device slidably connected to said bed and capable of being lifted from the plane of the bed, said upper ironing device being equipped with means for positioning the casing over the form-depression 120 in said bed when said upper ironing device is at one limit of its traverse.

7. In means of the character set forth, the combination of a bed provided with means for positioning a cover and provided 125 also with a form-depression, means for clamping the lower wall of a casing in said depression and holding the lower end flaps

of the cover against the margins of the inner surface of said lower wall, means for ironing the cover over the upper wall of said casing and depressing the margins of the cover over the edges of said upper wall, means for folding the rear tucks of the cover inwardly between the walls of the casing, and means for pressing inwardly and ironing the longitudinal flaps and end flaps of the cover, said means being adapted also to iron the infolded tucks against the back wall of the casing.

8. In means of the character set forth, the combination of a bed plate provided with means for positioning a cover and provided also with a form-depression, means for clamping the lower wall of a casing in said depression means for ironing the cover over the upper wall of said casing and folding the margins downwardly, a flap ironing device comprising a central member and arms pivotally connected therewith, and corner tab ironing clips adapted to be inserted between the corner portions of the walls of said casing while the flap ironing device is in inserted position.

9. In means of the character set forth, the combination of a bed provided with means for positioning a cover and provided with a form-depression, means for clamping one wall of a casing in said depression, a pivotally and slidably mounted upper ironing and pressing member, and means for supporting said upper member in standing position.

10. In means of the character set forth, the combination of a bed equipped near its front end with a form-depression, a transverse gage member and lateral gage members disposed back of said depression and adapted to position a cover on said bed, and

an upper ironing member provided with a form-depression adapted to accommodate the upper wall of a casing and its covering.

11. In means of the character set forth, the combination of a bed equipped near its front end with a form-depression, a transverse gage member and lateral gage members disposed back of said depression and adapted to position a cover on said bed, an upper ironing member provided with a form-depression adapted to accommodate the upper wall of a casing and its covering, and a pair of clamping devices mounted on said bed and adapted to be moved in position to clamp the end portions of the lower wall of the casing in the form-depression of said bed.

12. In means of the character set forth, the combination of a bed provided at its front end with a form-depression and provided back of said form-depression with means for positioning a cover on said bed, a pair of clamping members adapted to clamp the lower wall of a casing in said depression, a standard at the rear end of said bed, a pivotally and slidably mounted ironing and pressing device provided with a form-depression adapted to receive the upper wall of said casing, said last-mentioned device being adapted to be swung rearwardly and supported against said standard, and a spring adapted to engage the pivotal support of said ironing and pressing device when it is at the rear end of its traverse.

13. In means of the character set forth, the combination of a bed provided with cover-positioning means and a form-depression, and a movably mounted upper ironing and pressing member provided with a form-depression, for the purpose set forth.

CHARLES FISHER.
